JOINTED ASH PAN FOR COMBUSTIBLE GAS GENERATORS

John S. Haug, Philadelphia, Pa., assignor to
United Engineers and Constructors, Inc., Phila-
delphia, Pa., a corporation of Delaware

Application June 29, 1932, Serial No. 619,833

8 Claims. (Cl. 110—165)

The present invention relates generally to mechanically operated, ash extraction apparatus for combustible gas generators.

Such generators are provided with mechanical grates, usually rotating and provided with an ash pan which forms a support for the fuel bed and from which the ashes are discharged.

It is generally desirable to introduce the gas making fluids, as for instance air and steam, through a tuyère extending upward into the central portion of the lower part of the fuel bed, which tuyère is usually surrounded by the ash pan. The ash pan may rotate while the tuyère is stationary or vice versa, or both may rotate in the same direction or in opposite directions.

Due to the usual methods of introducing the gas making fluids and of operating the generator, temperature conditions are not uniform throughout any given horizontal cross section of the fuel bed. As a result different portions of the ash pan are exposed to different temperature conditions and the ash pan is not heated uniformly throughout.

Under certain operating conditions the inner portion of the ash pan is heated more highly than the outer or circumferential portion. As a result the outer portion acts somewhat as a hoop resisting the expansion of the inner portion, causing complicated strains to be set up in the outer portion which results frequently in cracks developing. Under other operating conditions the situation may be reversed with the outer portion more highly heated than the inner portion.

The principal object of the present invention is the provision of an expansion joint or joints between portions of the ash pan so that the various portions may expand in response to the unequal heating without setting up destructive strains.

The invention will be described in more detail in connection with the attached figures which form a part of the specification and which show its application to a particular type of mechanical grate, chosen for illustration.

Referring to the figures.

Figure 1 shows a vertical cross section of a water gas generator with a rotating mechanical grate including a rotating ash pan.

Figure 2 shows a vertical cross section of a portion of the ash pan showing an expansion joint.

Figure 3 shows a vertical cross section of the joint of Figure 2 between bolts.

Figure 4 shows a plan view of a portion of the ash pan of a modification.

Figure 5 shows a vertical cross section on line 5—5 of Figure 4, and

Figure 6 shows a detail of Figure 4 with deck plates removed.

Referring to Figure 1.

1 generally indicates a water gas generator adapted to contain the fuel bed 2, and provided with the air supply means 3 and steam supply means 4 for up air blasting and steaming respectively. 5 is the steam supply means for down steaming, 6 is the offtake for the blast gas and uprun water gas and 7 is the offtake for down-run water gas. 8 is an annular boiler water jacket with the feed water inlet 9 and steam off-take 10.

The generator is provided with a mechanical grate comprising the tuyère or blast distributor 11, extending upward into the fuel bed and, as shown somewhat diagrammatically, providing ports for the entrance of the gas making fluids 10 (air and steam) to the fuel bed and for leading off down run water gas from the fuel bed. The tuyère is mounted on the ash pan 12 which extends outwardly from the base of the tuyère and which is provided with the outwardly extending cutting ribs 13. The ash pan is supported on a sliding bearing indicated at 14 and is provided with the worm wheel 15 driven by the worm 16 so that the ash pan, cutting ribs and tuyère slowly revolve in the base of the fuel bed. The cutting ribs 13 grind or shear off clinker and, with the cooperation of plows 17, eject the clinker and ash into the ash pockets one of which is indicated at 18.

The ash pan is provided with an annular expansion joint indicated at 19 and shown in more detail in Figures 2 and 3.

Referring to Figures 2 and 3.

20 shows the outer part of an inner portion of the ash pan, while 21 shows the inner part of 40 an outer portion of the pan, in a vertical section taken, for example, at 19 in Figure 1. As shown in Figure 1, the ash pan illustrated has the general form of a low, truncated, upright cone.

The outer portion 21 of the pan is provided with the extension 22 which underlies the rim of the inner portion 20 of the pan and to which the inner portion is bolted as by the tap bolt 23. The bolt holes, one of which is shown at 24, are made over size to permit the two portions of the pan to slide relative to each other. The bolt holes in the two portions are arranged so that when the portions are bolted together unheated there is left the space 25 between them. The lip 26 of the inner portion of the pan overlies this space 55

to prevent the entrance of ash into the space. A small recess 21 is provided to form a pocket for any small quantity of ash which may work its way under the lip 26. The bolts are protected by being placed in recesses as 28.

As shown in Figure 2 the joint has been arranged so that the inner portion of the pan 20 may expand outwardly relative to the portion 21, sliding on the extension 22. The oversize bolt holes 24 and the space 25 provide the room for the relative movement.

Referring to Figure 3.

This shows a section of the ash pan between bolts. 29 shows one of a number of radial keys which fit into radial key ways in the inner and outer portions 20 and 21. The keys connect the inner and outer portions so that the inner portion of the pan rotates with the outer. The keys are free to expand radially inward at 30 and do not hinder the relative radial movement of the two portions of the pan.

Referring to Figures 4, 5 and 6.

These figures show an ash pan of the same general type as the ash pan of the previous figures but of modified construction.

The pan is formed by sectional deck plates secured to an underlying frame. The outer frame, indicated at 40, has bolted to it the outer deck plates 41, by an outer series of bolts indicated at 42, which pass through radially slotted bolt holes in the frame as indicated at 43 in Figure 6 and by an inner series of bolts indicated at 44 which pass through bolt holes 45 in the frame. The inner portion of the ash pan is made up of sections 46, bolted or otherwise jointed together as at 47 and also fastened to the frame 40 by the bolts 48 which pass through radially slotted holes 49 in the frame.

The frame is provided with the stiffening ribs 50 and carries the driving means as for instance the worm wheel 51. The surface 52 of the frame may slide on an annular bearing similar to 14 in Figure 1. A tuyère similar to 11 in Figure 1 may be mounted on the pan at 53.

It will be apparent that the inner portion of the pan may expand relative to the outer portion due to the provision of a space 54 between the ends of the inner and outer plates, and because of the provision of the slotted bolt holes 49 which provisions permit the inner portion of the pan to slide radially on the frame. The slotted bolt holes 43 permit the outer deck plates 41 to expand radially, sliding on the frame while the inner ends of these plates are held by the bolts 44.

As shown in the figures the outer deck plates are separated by radial spaces 55 which permit some expansion at right angles to the radius, the bolt holes being slightly larger than the bolts.

The inner and outer portions of the pan rotate together, the drive being transmitted through the bolts 48.

56 is a cutting rib similar to the ribs 13 in Figure 1.

The invention has been described in connection with a water gas generator and in connection with a certain type of grate. In its broader aspect it is applicable to grates of other types for producers, water gas generators and other types of shaft furnaces in which a column of fuel is supported by an ash pan which is subjected to unequal temperature conditions in its various portions. In the illustrations described the ash pan is shown provided with annular joints. Under certain conditions, especially with fuel beds of large diameter it may be desirable to provide a plurality of

such joints at various distances from the center. The exact position of the joint or joints with respect to the center of periphery of the pan will depend upon the type of furnace, method of air distribution and other operating conditions.

The provision of radial joints 55 between the deck plates, as illustrated in the outer portion of the pan shown in Figs. 4, 5 and 6, permits expansion to take place in the pan with no appreciable increase in the inner periphery of the portion provided with such joints. This makes it unnecessary to provide slotted bolt holes at the inner periphery of such deck plates and reduces the increase in diameter of the outer periphery on expansion. Also the radial joints provide for expansion due to local overheating of individual plates. It will be obvious that the radial joints may be provided between deck plates in the inner portion if desired.

I do not intend to be limited in the practice of my invention save as the scope of the prior art and of the attached claims may require.

I claim:

1. A grate for a combustible gas generator including an ash pan having an annular outer portion, an annular inner portion adjacent thereto, and means connecting said portions and providing for relative radial movement therebetween.

2. A grate for a combustible gas generator including an ash pan having an annular outer portion, an annular inner portion resting at its outer edge on said outer portion, and means connecting said portions and providing for relative movement therebetween.

3. A mechanical grate for a combustible gas generator including in combination an ash pan having an annular outer portion, an annular inner portion adjacent thereto, and bolts connecting said portions together, one of said portions having enlarged bolt holes therein to provide for radial sliding movement of said portions.

4. A mechanical grate for a combustible gas generator including an ash pan having an annular outer portion, an extension on the inner edge of said outer portion, an annular inner portion whose lower edge rests on said extension, means for connecting said portions so as to provide for radial sliding movement therebetween, and keys preventing relative rotary movement between said portions.

5. A mechanical grate for a combustible gas generator including an ash pan having an annular outer portion, an annular inner portion adjacent thereto, said portions having faces in sliding contact with each other, means connecting said portions together for sliding radial movement, means for preventing rotary movement between said portions, said portions being spaced to provide a chamber between their non-horizontal surfaces, and a lip on said inner portion overlying said chamber and the adjacent part of said outer portion.

6. A mechanical grate for a combustible gas generator including an ash pan having an underlying frame, outer deck plates secured to said frame, means for connecting said outer deck plates to said frame and providing for radial sliding movement between portions of said deck plates and said frame, inner deck plates secured to said frame, and means for attaching said inner deck plates to said frame and providing for relative radial movement between portions of said deck plates and said frame.

7. A mechanical grate for a combustible gas generator including an ash pan, said ash pan com-

- prising in combination, an underlying frame, outer deck plates secured to said frame, said outer deck plates being spaced apart to provide openings between them extending radially of
- 5 said ash pan, means for connecting said outer deck plates to said frame and providing for radial and circumferential movement between said deck plates and said frame, inner deck plates secured to said frame, and means for attaching said inner
- 10 deck plates to said frame and providing for relative radial movement between said inner deck plates and said frame.
8. A mechanical grate for a combustible gas generator including an ash pan, said ash pan comprising in combination, an underlying frame, outer deck plates secured to said frame, said outer deck plates being spaced apart and providing openings between them extending radially of said ash pan, inner deck plates secured to said frame, and means for attaching said deck plates to said frame and providing for relative radial movement between said deck plates and 10 said frame.
- 5

JOHN S. HAUG.
